TRACTOR TRACK SHOE

Norman E. Risk, Peoria, Ill., assignor to Caterpillar Tractor Co., Peoria, Ill., a corporation of California

Application March 14, 1949, Serial No. 1,391

Term of patent 14 years

(Cl. D90—20)

To all whom it may concern:

Be it known that I, Norman E. Risk, a citizen of the United States, residing in the city of Peoria, county of Peoria, State of Illinois, have invented a new, original, and ornamental Design for a Tractor Track Shoe, of which the following is a specification, reference being had to the accompanying drawing, forming part thereof.

In the drawing:

Fig. 1 is a perspective view illustrating the configuration of the ground engaging face of a tractor track shoe, embodying the design of the present invention; and

Fig. 2 is a similar view illustrating the opposite side of the same tractor track shoe.

I claim:

The ornamental design for a tractor track shoe, as shown.

NORMAN E. RISK.
